[57] **ABSTRACT**

A dredging device having a mounting plate for positioning the device on a vehicle and a slidable carriage movable on the plate. Means are included for sliding the carriage along the plate and locking it in a given location.

HYDRAULIC CLAMP FOR LATERALLY MOVABLE MOUNTED DREDGES

This invention relates to mounted dredges which are movably arranged on a guide which is attached by means of a slideable carriage to a carrier vehicle and which extends laterally to the latter's longitudinal axis. In particular, it relates to a clamping device designed to fix the slideable carriage in any desired position longitudinally along the lateral guide.

The state of the art shows mounted dredges in which the slideable carriage, which carries the outriggers and the digging tool, is clamped by means of two or more cylinders, similar to the arrangement used in parallel vises or disk brakes. This known type of clamping therefore takes place by the use of tension. The invention is intended to create a clamping device that locks the device in any given location. This clamping action is achieved with simple hydraulic means and can be easily achieved as well as maintained because of its structure and because it is not vulnerable to failure.

A clamping device for bearing slideable carriages having mounted dredges is characterized through a perpendicularly mountable plate which is held on a carrier vehicle and which has dove-tail-shaped chamfers on the upper and lower gliding pieces on the slideable carriage which grip or extend over the upper and lower edges of the mounting plate and which come to rest against the chamfers with correspondingly arranged wear-resistant strips, as well as by hydraulic cylinders which are arranged in the vicinity of the upper or lower edge of the mounting plate in the carriage. When power or stress is applied, the pistons of these hydraulic cylinders press against the plate and thus guarantee form locking clamping via the chamfers on the gliding pieces and the plate.

This idea offers the advantage that the carriage, which has a certain lateral extent, is held firmly in a form-locking manner by means of a very simple constructed device. In other words, it is held against the mounting plate in this manner, with all four corners and sides. As a result, the wear and tear of the carriage guide — which has occurred so far in lateral dredging, that is to say, when the outrigger is swung at an angle of about 90° toward the longitudinal axis of the carrier vehicle, can be extensively avoided, in comparison to the known designs. The clamping device according to the invention is not confined to slideable carriage for mounted dredges; instead, it also extends to other areas of application in which movable heavy equipment must be fixed in certain or preselected positions.

The invention will be described in greater detail below and with reference to the drawings wherein:

FIG. 1 is a perspective view of a dredge with a mounting plate which is shown held in a position at the tail end of a tractor;

FIG. 2 is a perspective view of a part of the mounting plate with the carriage guided on it;

FIG. 3 is an enlarged cross section through the mounting plate and the carriage.

A mounting plate 10 is held in position, for instance, on the tail end of a tractor, as shown in FIG. 1, and a slideable carriage 20 is guided in a movable manner. The outrigger of a dredger is positioned on the carriage on a vertical swinging axle. In the example illustrated in FIGS. 2 and 3, the mounting plate consists of a welded

construction with a plate 11 and with horizontally rubbing U-shaped reinforcement parts 12 which constitute a hollow frame with the plate. Provided on this hollow frame are suspension loops or other means of attachment (not shown), in order to establish a firm connection with the carrier vehicle. On the horizontal upper and lower edges of plate 10 there are provided chamfers 13 and 14, preferably at an angle of 45°, which, considered together, give a dove-tail guide for the carriage 20.

The carriage 20 is likewise made in the form of a welded construction and consists of upper and lower gliding pieces 21 and 22, which are firmly connected with each other via bracing parts 23, 24. Furthermore, horizontal plates 25 and 26 are welded onto the carriage 20. The vertical swivel axis of the dredge is guided in these plates.

Gliding pieces 21 and 22 of the carriage contain longitudinal grooves 27 and 28, one of whose side wall is chamfered in adaptation to the chamfers 13 and 14 of plate 11, likewise at an angle of 45°, each time. Interchangeable wear-resistant guide strips 29 may be attached to these chamfers of grooves 27 and 28. The upper and lower gliding pieces 21 and 22 can, in each case, consist of two individual parts which constitute the lateral ends and corners of carriage 20 and which are connected to each other with the help of bracing parts 23, 24.

Near the lateral ends of the upper gliding piece 21, horizontal glide bushings 30 are built in, according to FIG. 3. In each of these glide bushings, a freely movable piston 31 is guided. One of the end surfaces of pistons 31 is opposite the mounting plate 10 while the other end surface can be stressed hydraulically by a tightly sealed pressure chamber inside glide bushing 30. The pressure compartment or chamber 32 is made tight, on the one hand, via piston seals 33 and, on the other hand, via a lid 34 which closes the glide bushing 30. A pressure-medium duct 35 is provided in that lid. This duct is connected to the hydraulic power supply of the dredge.

FIG. 3 shows the condition in which the pistons 31 are under hydraulic tension, whereby they press against the mounting plate 10 and lock the carriage 20. On the basis of this procedure, gliding pieces 21 and 22 come to rest against chamfers 13 and 14 of plate 11 with their wear-resistant strips 29 so that the carriage remains firm also when the dredger's outrigger is swung around at an angle of 90°. If the bearing sled is to be adjusted laterally toward the longitudinal axis of the vehicle, then the hydraulic pressure in pressure chamber 32 is reduced. In the arrangement of the cylinders as shown in the drawing, the pistons 31 are pressed back over the upper chamfer by the inherent weight of the bearing sled and the dredge outrigger, so that there is no need for a special recovery spring for the pistons. As the result of this, a leeway develops along the lower chamfer, so that the carriage 20 can be moved laterally.

The hydraulic cylinders, constituted by glide bushings 30 and pistons 31, can be replaced by clamping screws whose rotation motion is synchronized via a common mechanical or hydraulic drive. Of course, pistons 31 can also be built into the lower gliding pieces 22 in order to initiate the clamping of the carriage from the lower part of built-on plate 10.

I claim:

1. A device for mounting a slidable carriage for a dredge to a plate comprising:
  - a. a mounting plated for attachment to a vehicle, said mounting plate having a thin, planar surface and including a pair of U-shaped hollow reinforcing members secured to one side thereof,
  - b. a slidable carriage for carrying the dredge,
  - c. said mounting plate having top and bottom edges with beveled chamfers, said beveled chamfers being only beveled in a direction away from said carriage toward said one side,
  - d. said slidable carriage including upper and lower glide pieces having complementary chamfers for receiving said beveled chamfers, said glide pieces being connected by bracing means,
  - e. at least one hydraulic cylinder on said slidable car-

- riage arranged adjacent to said top edge of said mounting plate,
  - f. piston means in said hydraulic cylinder for locking said slidable carriage to said mounting plate,
  - g. said cylinder including a pressure medium duct means for providing fluid to said cylinder, whereby said piston abuts said mounting plate when fluid is applied thereto.
2. A device according to claim 1 wherein said 10 hydraulic cylinders include a plate at one end and a glide bushing surrounding said piston.
  3. A device according to claim 1 wherein said complementary chamfers include wear-resistant strips.
  4. A device according to claim 1 wherein said 15 beveled chamfers are at an angle of approximately 45°.
